UNITED STATES PATENT OFFICE.

RICHARD KÖRNER, OF DRESDEN, SAXONY, GERMANY.

WINDOW FLOWER-STAND.

SPECIFICATION forming part of Letters Patent No. 285,140, dated September 18, 1883.

Application filed April 23, 1883. (No model.)

To all whom it may concern:

Be it known that I, RICHARD KÖRNER, of the city of Dresden, in the Kingdom of Saxony and German Empire, have invented certain new and useful Improvements in Adjustable Window Flower-Stands, of which the following is a full and clear specification.

My invention relates to improvements in adjustable window flower-stands. The stands or parapets used hitherto for holding or protecting objects placed on the window-sill from falling, and which also serve as ornaments to the building, would have been employed to a much greater extent if the fixing of the same had not presented so many difficulties.

According to the old system, the window-sill, or breadth of the window, had to be carefully measured and the stand made to fit exactly, so that on removing from one house to another the said flower stands or parapets had either to be sold for old iron or left to the next following tenant for nothing, or next to nothing, it being extremely seldom that such said stands or parapets would fit the windows in the new dwelling.

The object of the present invention is to produce an ingeniously-constructed window flower stand or parapet which can be adapted to windows of various breadths or widths, can be readily fixed and as readily removed, can be packed or stored in an exceedingly small space, and can be made at a very low price.

The accompanying drawing shows a view of my improved window flower stand or parapet, which consists of straight or ornamental diagonally-arranged bars, rods, or strips, of metal or other suitable material, *d*, which bars, rods, or strips are loosely riveted, screwed, or otherwise attached to each other at the crossing points, so that the flower stand or parapet can be shortened or lengthened at will by moving the rods or strips so that the same will stand at a different angle to each other.

For very narrow windows some of the bars or strips can be removed, and for very broad windows an appropriate number of the bars can be added, in order to avoid the too angular position to each other. It is advantageous to attach at least some of the center bars, rods, or strips by means of screws, or screws and nuts. The ends of the railing forming

the front of the said flower stand or parapet are attached to the inner surface of the window-opening or wall, or to the frame-work of the window, by means of T-formed or other suitably-formed holders or attachments, *h*, which are fastened to the upper and lower crossing point of the bars on the one part, and to the wall *g*, to the side of the window, or to the frame-work of the window by means of suitable screws, bolts, or their equivalents.

The holders are provided with suitable slots, *s*, through which the screws, or their equivalents, are passed, which slots can be made in the vertical or horizontal parts of the said holders, or both. This arrangement admits of the holder being placed at an upper or lower crossing-point or junction, even when the said bars stand at a more acute or obtuse angle. By employing this method of attachment it is also not necessary to be so extremely particular in inserting the wooden plug or its equivalent, into which the attaching screw or bolt is screwed, as the horizontal and vertical slots permit a considerable adjustment of the holder *h* both in the vertical and horizontal direction.

In order to prevent the said flower-stand or the center of the railing to be bulged out, angular holders *h* are employed, which holders are also provided with slots, in order to enable the said holder to be adjusted according as the circumstances may require. These holders are attached on the one end to the stand or parapet, and on the other end to the window-sill *b*.

Having now described my said invention for improvements in adjustable window flower-stands, I wish it to be understood that what I claim, and desire to secure by Letters Patent, is—

The combination of the bars *d*, crossing each other, and hinged together loosely, having vertically-disposed holders at the ends and on the side or sides, said holders being slotted to admit of adjustment with the angular slotted pieces which engage with the window sill and frame, substantially as herein set forth.

RICHARD KÖRNER.
